UNITED STATES PATENT OFFICE.

AUGUST M. H. DE BRUYCKER, OF NEW YORK, N. Y.

NOISELESS ASH-CAN.

1,028,672.

Specification of Letters Patent.

Patented June 4, 1912.

Application filed September 7, 1911. Serial No. 648,023.

To all whom it may concern:

Be it known that I, AUGUST M. H. DE BRUYCKER, a citizen of the United States, and a resident of the city of New York, 5 borough of Brooklyn, in the county of Kings and State of New York, have invented a new and Improved Noiseless Ash-Can, of which the following is a full, clear, and exact description.

10 The object of the invention is to provide a new and improved ash can arranged to permit of moving the can over pavements, floors and the like, or bumping one can against the other without producing the 15 undesirable noise now incident to handling metallic ash cans of the usual construction.

For the purpose mentioned, use is made 20 of a ring of rope held between retaining members formed on bands or hoops attached to the body or cover of the ash can, the said bands or hoops also forming reinforcing members for the body or cover.

A practical embodiment of the invention 25 is represented in the accompanying drawings forming a part of this specification, in which similar characters of reference indicate corresponding parts in all the views.

Figure 1 is a perspective view of the ash can; Fig. 2 is a sectional side elevation of 30 the same; Fig. 3 is a plan view of the same partly broken out; Fig. 4 is a sectional side elevation of a modified form of the ash can; and Fig. 5 is a sectional side elevation of the ash can cover.

35 The body A of the ash can is provided near its upper end with metallic bands B and C having their opposite edges provided with flanges B', C' for clampingly engaging a ring D made of rope or similar material, 40 and retained in place by the said flanges B' and C', in such a manner that a portion of the rope ring D extends outwardly beyond the flanges to form a noiseless abutment in case adjacent cans abut against each other. 45 The bands B and C are fastened to the body A by suitable means, such as rivets E, and the said bands strongly reinforce the upper end of the body A besides forming a retaining device for the rope ring D, the flange B' of the upper band B also forming a rest 50 for the noiseless edge of a cover to be hereinafter described.

A rope ring F forms the base for the ash can to rest on, and this rope ring F is 55 clamped between the flanges H' and G' of retaining and reinforcing rings G and H

fastened by rivets I or other means to the lower end of the body A, the said rivets being also used for fastening the flange J' of the cam bottom J in position on 60 the body A. Openings K are made in the lower end of the body A below the bottom J, the openings also passing through the bands G and H, so as to prevent the trapping of air in the lower portion of the 65 body A.

It will be noticed that by the arrangement described, the ash can can be readily moved over a pavement, floor or the like without producing any undesirable noise, 70 as the rope F supports the can body on the pavement or floor and hence practically renders the ash can noiseless while moving the same from one place to another for dumping ashes and returning the ash can. 75

For ash cans having a body A' provided with a bottom A², as shown in Fig. 4, the rope ring F' is held in place by flanges G² and H² of metallic bands G³, H³ riveted to the sides of the body A' and the bottom 80 A², as plainly indicated in Fig. 3. If desired, a ring L, of asbestos or a like material, is interposed between the rope ring F' and the body A' at the junction of the latter with the bottom A², the said asbestos 85 ring forming a cushion for the rope ring F'.

In order to render the cover Q for the ash can noiseless when placing the same on the sidewalk, floor or other support, use is made of a rope ring O, engaged at opposite 90 sides by flanges P' and Q' the latter of which is formed on the peripheral edge of the cover, and the former of which is formed on a band P secured on said cover edge, so that the rope ring O extends 95 downwardly beyond the flanges P' and Q' and hence rests on the sidewalk or floor, to support the cover and to render the same practically noiseless when throwing the cover on the sidewalk or the like 100 and also when properly placed on the body A, to rest on the flange B' as before mentioned.

Having thus described my invention, I claim as new and desire to secure by Letters Patent:

An ash can comprising a cylindrical body open at both ends, a base extending within, and closing the lower end of said body, said base having a circular flange disposed 110 against the extreme lower body edge, and terminating in an outwardly bent and in-

wardly curved portion, a band disposed around the inside of said flange and having a grooved portion opposite said grooved flanged portion, a buffer ring partially disposed within said opposite curved portion of said flange and said band, and means to secure said band and said flange to the lower body edge whereby to clamp said buffer ring in position.

In testimony whereof I have signed my name to this specification in the presence of the subscribing witnesses.

AUGUST M. H. DE BRUYCKER.

Witnesses:

E. T. NEWMAN,
THOMAS CONNOR,
SIGMUND HONNEKER.
